UNITED STATES PATENT OFFICE.

JOHN E. EUTH, OF CINCINNATI, OHIO, ASSIGNOR TO THE GLOBE REGISTER COMPANY,
OF CINCINNATI, OHIO, A CORPORATION OF OHIO.

WEB ALIGNING, TENSIONING, AND CUTTING DEVICE.

Application filed September 3, 1925. Serial No. 54,254.

This invention is an improvement on the device disclosed in copending application Serial No. 24,885, filed April 21, 1925 by Blanton M. Boyd. In the device disclosed in this copending application the essential feature consists of a series of shutters or slats in cooperation with each of which a roller is provided for limited movement therewith during movement of the webs which pass over the rollers, and in which the shutters are also movable with relation to the rollers, but in a different direction and for a different purpose than the roller movement. Such an arrangement operates very effectively for a relatively small number of webs such as are employed for certain purposes, but is quite unsuited for devices in which the number of webs which have to be used is relatively large.

In the present invention the general idea of having shutters and rollers is preserved, but the specific arrangement and operation of these elements relatively to each other is changed in certain respects to comply with the objects of the invention. One of these objects is to produce a web aligning and tensioning device which is adapted to operate successfully to align and tension any desired number of webs upon a platen adapted to support them and upon which they are to be filled in. Another object is to produce a web aligning and tensioning device in which the existing means provided for severing portions of the web is so united with the means for operating the aligning and tensioning device that but a single operation is necessary in order to operate both.

These and other objects are attained in the device described in the following specification and illustrated in the accompanying drawings, in which:

Fig. 1 is a perspective view of the device embodying my invention, in the positions its related parts assume when the webs are ready for use.

Fig. 2 is a view similar to Fig. 1, showing the positions assumed by the parts during certain periods of the operation of the device.

Fig. 3 is a somewhat enlarged fragmental perspective view of a portion of the apparatus in the condition represented in Fig. 1, but showing a web in position therewith.

Fig. 4 is a somewhat enlarged fragmental

perspective view of a portion of the apparatus in the condition represented in Fig. 2, but showing a web in position therewith.

Fig. 5 is a somewhat diagrammatic perspective view showing the means for operating my improved device, and the manner in which I have connected it for cooperative relation with the severing mechanism by means of which the used portions of the webs are removed from the source of web supply.

In illustrating the embodiment of my invention I have shown a stand which forms a part of a well known style of typewriter equipment. This stand consists of such main features as legs 6 and 7 which support a table or platen 8 which has side rails 9 and 10 upon which the typewriter moves. At the forward edge of the platen a tearing knife 11 is located for movement substantially vertically away from and toward the platen so as to clamp webs upon the platen preparatory to the tearing operation as well as for another purpose which will be explained, or to release the webs so that fresh portions may be provided and the filled in portions extended beyond the platen for tearing them off. The tearing knife is rendered movable by mounting it on arms 12 and 13 which are pivoted at points 14 and 15, see Fig. 5, springs 16 and 17 being so connected therewith as to hold the knife normally in clamping engagement with the webs on the platen. A rocker arm 18 which is mounted on a pivot bar 18^a, causes the knife 11 to be operated by extending beneath it and having attached to it a link 19 which is attached to a foot treadle 20 upon a bar 21, so that downward pressure upon the treadle will lift the knife. The device which has thus far been described is but the usual equipment which is necessary as a part of the style of typewriter referred to above, and I will now describe the part which contains the features of novelty contained herein.

Rearward extensions of the side rails 9 and 10 to an extent to overhang the legs, is provided. This rearwardly extending pair of rails carries between them a frame which consists of side members 22 and 23 which are held apart by a series of slats or shutters 24 attached rigidly thereto and spaced from each other. Each of the side members is

hollow and contains a sliding bar 25 which has slight forward and backward movement. These bars at their forward ends are attached to each other by a rod 26, the ends of which extend through slots 27 in the inner wall of each of the side members 22 and 23. The forward termination of each of the slots 27 is a downwardly extending portion 28 into which the ends of the rod may be moved 10 at such times as it may be necessary to hold the bars 25 at their forward limit of movement, as will be explained. Each of the bars 25 is notched at regular intervals to provide a series of upstanding fingers 29 which extend across the slots 27 as shown in Figs. 1 and 2. These fingers occupy positions back of the ends 30 of a series of rollers 31 extending between the side members 22 and 23, the ends of the rollers being held yieldingly against the fingers by springs 32 inside the side members. There are as many rollers as there are slats 24, with the spacing of the rollers such that each roller will be in the same relation to the slat beneath it, with 25 one roller in cooperation with each slat. Thus the effect of a pull upon rod 26 will be to draw bars 25 forwardly, thereby moving the rollers from off their cooperating slats and opening a space between each roller and 30 its slat, the former position being shown in Fig. 3 and the latter in Fig. 4. At this time it may be pointed out that although I have described the slots 27 as being continuous and occupied by the ends of all the rollers, I 35 may as readily make individual slots for the occupancy of but one roller end as suggested in Figs. 3 and 4. In such a construction it may be desirable to slant each slot so that each roller, in addition to moving forwardly 40 away from its cooperating slat, will also be lifted somewhat during such movement so as to still further clear the slat, as is also suggested in Figs. 3 and 4. And now, in order that the operation of these rollers may be ac- 45 complished conveniently and at the proper time in coordination with the operation of the tearing knife 11, I attach a cable 33 to the rod 26 and to the treadle 20 so that simultaneous operation of the rollers and the 50 knife will take place when the treadle is operated. A feature to which I call attention is that which I have employed to bring about the desired tension upon the springs 32 governing the movement of rollers 26. The 55 lower ends of the springs are attached to a strip 34 which is located in each of and is slideable with relation to the side members 22 and 23. Backward movement of these strips 34 tensions the spring and exerts the 60 desired degree of pull upon the rollers, a set screw 35 having been provided to secure each strip in its adjusted position.

I will now describe the operation of the 65 device I have just described, and in doing so will refer frequently to the enlarged frag-

mental perspective views shown in Figs. 3 and 4. Inasmuch as this invention is a development of that disclosed in the copending application referred to above, it will be understood that the source of web supply may be from a packet or a roll or rolls located beneath the shutters and rollers, and that each web 36 (see Figs. 3 and 4) is brought up from beneath these elements. The threading of these webs over the rollers 31 is accomplished by pressing upon the treadle 20, which draws all the rollers forwardly into positions away from the shutters. The rollers are locked in this position by pressing rod 26 downwardly into ends 28 of slots 27. 70 Each web is then passed over its one of the rollers and drawn forwardly so that its apertures 37 and 38 may be placed upon the hooks 39 and 40 at the forward edge of the platen 8. The rod 26 is then released and 75 the rollers 31 allowed to return. This allows slight backward movement of each web and permits the roller over which it passes to pass onto its cooperating shutter, as shown in Fig. 3, thus snubbing or checking the feed 80 of the web from its roll, but operating to draw the platen supported portion thereof into taut condition upon the platen 8. If, because of the thickness or stiffness of the web material, the rollers do not draw the 85 webs sufficiently tight to lie flat upon the platen, strips 34 may be shifted backwardly until the springs 32 exert the required degree of tension to bring about the desired results. It may be mentioned at this time that 90 the blade 11 is lifted at the time the rollers are drawing forwardly and that the blade must be raised in order that each of the webs may have their apertures hooked over hooks 39 and 40. Each time each web is 95 stretched upon the platen it is because of the bringing of the walls of its apertures 37 and 38 into engagement with the walls of the hooks. This operation then serves also to obtain accurate registration of any printed 100 forms which may have been provided on the webs, as well as to obtain a web tensioning action. Because of the connection of both the knife and rollers with the single operating medium 20, simultaneous operation of 105 both is obtained.

Now, assuming the device to have been properly threaded, the platen supported portions of the web are used by filling them in with the desired notations. The treadle 20 is then moved downwardly, thus lifting knife 11 and drawing forwardly all the rollers simultaneously. This enables the forward edges of the webs to be grasped and 110 also frees the webs from the shutters so that there is no drag thereon other than the pull necessary to unwind the webs from their supply roll or rolls. In this manner a larger 115 number of copies may be made simultaneously than would otherwise be possible,

120

125

130

because of the easy manipulation, the independent control of each web and the consequent uniformity and positive accuracy with which all the webs are aligned. As in all 5 copy work obtained by using superposed webs, carbon sheets interleave the webs, the particular manner of employing such carbon sheets being well known and not needing description as applied to the style of stand 10 I have shown and described.

Having thus described my invention, what I claim is:

1. A web aligning, tensioning and cutting device comprising in combination with a platen adapted to receive and support a series of webs from a source of supply, a series of rollers over each of which one of the webs is adapted to be drawn before its passage to the platen, a series of slats corresponding in number to the number of rollers, with each of the slats designed for cooperation with but one of the rollers, means for mounting said rollers for movement toward and away from the slats, a web cutting knife, a second means adapted simultaneously to operate the knife and to move all the rollers away from the slats preparatory to web movement over the rollers, and a separate means adapted to be brought 20 into action functioning the independent return movement of the knife and the rollers toward the slats upon restoration of the second mentioned means to normal condition.

2. A web aligning, tensioning and cutting device comprising in combination with a platen adapted to receive and support a series of webs from a source of supply, a series of rollers over each of which one of the webs is adapted to be drawn before its passage to the platen, a series of slats corresponding in number to the number of rollers, with each of the slats designed for cooperation with but one of the rollers, means for mounting said rollers for movement toward and away from the slats, movement away from the slats being arranged for simultaneous movement of all the rollers previous to web feeding movement over the platen, movement toward the slats being arranged for independent movement of each roller in response to its controlled web movement.

3. A web aligning and tensioning device comprising in combination with a platen adapted to receive and support a series of webs from a source of supply, a series of rollers over each of which one of the webs is adapted to be drawn before its passage to the platen, a series of slats corresponding in number to the number of rollers, with each 55 of the slats designed for cooperation with but one of the rollers, means for mounting said rollers for movement toward and away from the slats, means adapted to move the rollers from the slats preparatory to web feeding movement, separate means adapted

to reverse the movement of the rollers upon release of the first mentioned means, and an aligning device adapted when the first mentioned means is released to arrest reverse movement of the rollers in response to operation of the separate means, whereby the webs are tensioned upon the platen.

4. A web aligning, tensioning and cutting device comprising in combination with a platen adapted to receive and support a series of webs from a source of supply, a series of rollers over each of which one of the webs is adapted to be drawn before its passage to the platen, a series of slats corresponding in number to the number of rollers and relatively stationary to the rollers, with each of the slats designed for cooperation with but one of the rollers, means for mounting said rollers for movement toward and away from the slats, means for moving the rollers from the slats to permit movement of the webs over the platen from their source of supply, and separate means for each roller adapted to be brought into action functioning the independent movement of each roller toward its one of the slats upon restoration of the first mentioned means to normal.

5. A web aligning, tensioning and cutting device comprising in combination with a platen adapted to receive and support a series of webs from a source of supply, a series of rollers over each of which one of the webs is adapted to be drawn before its passage to the platen, a series of slats corresponding in number to the number of rollers and relatively stationary to the rollers, with each of the slats designed for cooperation with but one of the rollers, means for mounting said rollers for movement toward and away from the slats, means for moving all the rollers from the slats simultaneously to permit movement of the webs over the platen from their source of supply, and separate means for each roller adapted to be brought into action functioning the movement of the rollers toward the slats upon restoration of the first mentioned means to normal.

6. A web aligning, tensioning and cutting device comprising in combination with a platen adapted to receive and support a series of webs from a source of supply, a series of rollers over each of which one of the webs is adapted to be drawn before its passage to the platen, a series of slats corresponding in number to the number of rollers and relatively stationary to the rollers, with each of the slats designed for cooperation with but one of the rollers, means for mounting said rollers for movement toward and away from the slats, means for moving all the rollers from the slats simultaneously to permit movement of the webs over the platen from their source of

supply, and separate means for each roller adapted to be brought into action functioning the independent movement of each roller toward its one of the slats upon restoration of the first mentioned means to normal.

7. A web aligning, tensioning and cutting device comprising in combination with a platen adapted to receive and support a series of webs from a source of supply, a series of rollers over each of which one of the webs is adapted to be drawn before its passage to the platen, a series of slats corresponding in number to the number of rollers and relatively stationary to the rollers, with each of the slats designed for cooperation with but one of the rollers, means for mounting said rollers for movement toward and away from the slats, a web cutting knife, a second means adapted simultaneously to operate the knife and to move all the rollers away from the slats preparatory to web movement over the rollers, and a separate means adapted to be brought into action functioning the independent return movement of the knife and each of the rollers toward their respective slats upon restoration

of the second mentioned means to normal condition.

8. A web aligning, tensioning and cutting device comprising a platen, a series of perforated webs adapted to be drawn across the platen and to be supported thereby, a web tensioning device at the side of the device from which the webs are delivered, a web aligning pin at the side of the platen toward which the webs are moved, adapted to enter the web perforations when brought to register therewith, a web tearing knife, and means adapted to clamp the knife on the webs adjacent to the aligning pin after said tensioning device has operated to align the webs on the pin and secure web tension thereby of the platen supported portions thereof, said tensioning device and said knife operating means having a single operating mechanism adapted to produce simultaneous conditioning actuation of said device and means preparatory to aligning and tensioning operation thereof.

In testimony whereof I have hereunto affixed my signature.

JOHN E. EUTH.
